SWEATER

Hans Boepple, New York, N. Y.

Application May 7, 1958, Serial No. 50,791

Term of patent 3½ years

(Cl. D3—4)

The figure is a front view of a sweater showing my new design.

The rear of the sweater is substantially the same in appearance to the front shown, except for the omission of the front closure.

I claim:

The ornamental design for a sweater, substantially as shown and described.
